UNITED STATES PATENT OFFICE.

NORMAN EUSTACE DAVIS, OF CHENE BOURG, NEAR GENEVA, SWITZERLAND, AS
SIGNOR TO RADIO CORPORATION OF AMERICA, A CORPORATION OF DELAWARE.

WIRELESS TRANSMITTING APPARATUS.

Application filed December 3, 1921. Serial No. 519,797.

To all whom it may concern:

Be it known that I, NORMAN EUSTACE DAVIS, a subject of Great Britain, residing at Hotel des 4 Nations, Chene Bourg, Switzerland, near Geneva, have invented certain new and useful Improvements in Wireless Transmitting Apparatus, of which the following is a specification accompanied by drawings.

10 According to a method of transmitting wireless signals which is now frequently used a coil which is coupled to the aerial circuit is shortcircuited by the sending key. While this arrangement has certain advantages, it has also certain disadvantages, especially for rapid working; some of these are due to the fact that while the actual signal is made when the key opens and the coupling coil is thus unshorted, the 20 signal is only cut off when the key contact has travelled across the gap between it and its fixed contact.

According to this invention signalling is effected by shorting and unshorting a coil 25 coupled to the aerial circuit but the signal is made when the key closes. This is effected by employing two independent coupling coils so arranged that with both in circuit they are in opposition and the current in the aerial is therefore practically nil. A sending key is so arranged that when 30 it is closed one of these coils is short-circuited, while the other coil becomes effective.

35 The invention is illustrated by the accompanying diagram, in which A is an aerial having coupled to it two coils B and C so arranged that with both in circuit they are in opposition and the current in 40 the aerial is therefore practically nil. These two coils form part of an oscillatory circuit D in which oscillations can be set up, say, by a valve generator. The coil C can be shortcircuited by a signalling key E. 45 When the key contacts are closed, the coil C is shortcircuited and the full energy is passed to the aerial by coil B.

In order to avoid sparking at the key 50 contacts it is desirable that the coil C should have a small self inductance and that the leads to and from the key should be as short as possible and of small impedance.

As it can be arranged that there is prac-

tically no change in operation of the transmitting set with the key opened or closed 55 the wave length emitted is constant and also as signals are made with the key correctly connected the Morse formation is perfect. For medium powers owing to the absence of sparking and potential it is possible to use an ordinary light relay as the signalling key, so that a great increase of speed of transmission results, the receiving station at the same time being able to make full use of syntonation available and successfully to employ mechanical recording apparatus.

Having described my invention, what I claim is:

1. A wireless telegraph transmitter in 70 which signals and silence periods are effected by shorting and unshorting respectively by means of a key a coil in a tuned circuit coupled to the aerial, characterized in that the signal is made by the closing of 75 the key while maintaining the radiated frequency constant.

2. The method of operating a wireless telegraph transmitter having a coil in a 80 tuned circuit coupled to an aerial and means for shorting and unshorting said coil which consists in making the signal when the key is closed and the silence periods when the key is open while maintaining the radiated frequency constant.

3. The method of operating a wireless telegraph transmitter having a coil in a 85 tuned circuit coupled to an aerial and means for shorting and unshorting said coil which consists in shorting the coil to produce a 90 signal and unshorting the coil to produce a silence period while maintaining the radiated frequency constant.

4. The method of operating a wireless telegraph transmitter having a coil in a 95 tuned circuit coupled to an aerial and means for shorting and unshorting said coil which consists in shorting the coil while maintaining the tuning substantially constant to produce a signal and unshorting the coil to produce a silence period.

5. The method of operating a wireless telegraph transmitter having a coil in a tuned circuit coupled to an aerial which consists in uncoupling said coil from the aerial 105 to produce a signal and coupling said coil

- to the aerial to produce a silence period while maintaining the radiated frequency constant.
6. The method of operating a wireless 5 telegraph transmitter having a coil in a tuned circuit coupled to an aerial and means for shorting and unshorting said coil which consists in producing a signal by uncoupling said coil from the aerial by shorting it and producing a silence period by coupling said coil to the aerial by unshorting it while maintaining the radiated frequency constant.
7. The method of operating a wireless 10 telegraph transmitter having a coil in a tuned circuit, coupled to an aerial, which consists in producing a signal by uncoupling said coil from the aerial while maintaining said tuning substantially constant and producing a silence period by coupling said coil to the aerial.
8. In a wireless telegraph transmitter an aerial having two coils in a tuned circuit 15 coupled thereto in opposition to each other and a means adapted to shortcircuit one of the coils.
9. In a wireless telegraph transmitter, a tuned primary circuit, a secondary circuit, a plurality of coils in opposition in the primary circuit and coupled to the other circuit and means for short circuiting one of said coils. 20
10. In a wireless telegraph transmitter, a tuned primary circuit, a secondary circuit, a plurality of coils in said primary circuit in opposition, coupled to the secondary circuit and means for short circuiting one of said coils. 25
11. In a wireless telegraph transmitter, a tuned primary circuit, a secondary circuit, a pair of coupling coils between said circuits 30 arranged in opposition, said coils having a small co-efficient of self induction and means for shortcircuiting one of said coils.

NORMAN EUSTACE DAVIS.
